ATTORNEY.

UNITED STATES PATENT OFFICE.

CHARLES GOODWIN, OF EAST PROVIDENCE, RHODE ISLAND.

EYEGLASS-HOLDER.

1,043,092.

Specification of Letters Patent.

Patented Nov. 5, 1912.

Application filed August 3, 1911. Serial No. 642,121.

To all whom it may concern:

Be it known that I, CHARLES GOODWIN, a citizen of the United States, residing at East Providence, in the county of Providence and State of Rhode Island, have invented certain new and useful Improvements in Eyeglass-Holders, of which the following is a specification.

My invention relates to that class of eyeglass holders which comprises a reel for winding the eyeglass chain inclosed in a housing adapted for attachment to the clothing.

The objects of my invention are primarily simplicity and cheapness of construction, a reduction of the number of constituent parts, and facility, and certainty of travel of the chain. It is sought further to furnish a means for insuring a uniform distance of travel of the chain during use of the eyeglasses and obviate the necessity of repeatedly jerking the chain to catch or release a pawl locking reel as required in present structures.

To the above ends essentially my invention consists in such novel parts and combinations of parts as fall within the scope of the appended claims.

In the accompanying drawings which form a part of this specification and wherein like reference characters indicate like parts throughout the views, Figures 1 and 2 are front and side elevations respectively of my novel eyeglass holder, Fig. 3, a section of the same on line $x-x$ of Fig. 2, Fig. 4 a diametrical section of the same, Figs. 5 and 6 side elevations of the back member and cover respectively, Fig. 7, a diametrical section of the reel web, Fig. 8, a side elevation of the reel, and Fig. 9, a plan of the bearing plate for the spring.

The holder casing in the present instance comprises a back plate 10 having a side wall or flange 11 provided with an opening 12. The material of the plate 10 at its center is drawn inwardly forming a tubular sleeve or bearing 14 which is longitudinally slit to form an outturned finger 16 inclined from the base of the sleeve.

Attached to the back face of the plate 10 in any usual convenient manner is a fabric engaging device consisting in this instance of a joint member 18, catch 19, and pin tongue 20. A cover completes the casing, consisting of a front plate 22 having a marginal flange 23 frictionally engaging and

overlapping the flange 11, and provided with an oblong longitudinal opening 24 which registers with the opening 12. The opening 24 is preferably of less width at one end as at 25 and the material surrounding this retracted portion is preferably concaved or dished to form a seat or cavity 26, best seen in Fig. 6 wherein the chain is omitted. Loosely mounted in the bearing 14 is a tubular hub 28 centrally located in and integral with a plate 29 forming the web portion of a reel, said plate being also provided with a flange 30 of the same depth as the hub 28.

A lip 31 is cut from the body of the flange 30. The looped end 32 of a volute spring 33 engages the lip 31 while its other end is looped as at 34 upon the finger 16. The spring is inclosed by the flange 30 and abuts against a bearing or space plate 35 resting against the inner face of the plate 29 and provided with a central opening 37. The plate is provided with a peripheral notch 39. The described reel web has fixed upon its flange 30 a cylindrical rim 41 having outturned flanges 42 extending from its ends. The rim 41 is provided with an opening 44 registering with the opening 39 in the plate 35, whereby one end of the chain may be readily affixed in position. In these openings is held by friction or otherwise the end link 46 of a chain 47 wound about the rim 41 of the drum and passes through the openings 12, 24, of the casing. This end link 46 is passed through the coincident openings 39 and 44, as seen in Fig. 3, the said link being then turned at an angle to the next adjacent link, which latter lies in said openings and the end link 46 bearing against the inner wall, as seen in Fig. 3, prevents displacement of the chain. The chain is provided at one end with a snap 49, and intermediate its length is a ball 50 of greater dimensions than the portion 25 of the opening in the flange 14, but of less dimension than the slot portion 24. The ball is located at such a distance from the snap as to allow the requisite length of chain for the use of the operator while the eyeglasses are in use.

The spring 33 acting upon the reel normally winds the chain tight within the casing holding the snap 49 tight against the casing. When it is desired to use the eyeglasses the operator pulls the chain outwardly through the larger portion 24 of the opening until the ball 50 emerges. The

direction of the pull upon the chain is then changed to bring the latter in the portion 25 of the opening, and the chain is then released; whereupon the ball is pulled by the 5 action of the spring into and retained in its concave seat 26, where it remains until the operator discontinues the use of the eyeglasses.

What I claim is,—

- 10 1. In a device of the type set forth, the combination with the casing provided in the fixed wall thereof with an opening of elongated form, reduced in width at one end, of a reel rotatably mounted in the casing, a 15 chain upon the reel extending through said opening, means for exerting tension upon the reel, a snap upon the chain exterior of the casing, and means upon an intermediate portion of the chain adapted to engage a 20 fixed wall of the casing for stopping the travel of the chain, said means being movable through the enlarged portion of said opening, said fixed wall being provided with a depression to receive said means.
- 25 2. In a device of the type set forth, a casing provided in a fixed wall thereof with an opening having a broad portion and a narrow portion, a reel rotatably mounted in the casing, means exerting tension on the reel, a 30 chain upon the reel extending through the opening, a snap upon the chain exterior of the casing, and an enlargement upon an intermediate portion of the chain movable through the enlarged portion of the opening 35 and engageable with the fixed walls of the narrower portion of the opening to stop the travel of the chain, said casing being provided at the end of the narrow portion of the opening with inwardly dished walls to form 40 a seat for said enlargement.
3. In a device of the type set forth, the combination with a casing comprising a front and back plate, of a tubular bearing upon the back plate, a reel within the casing, 45 a hub integral with the reel and extending into the bearing, a spring surrounding the

bearing and attached to the bearing and to the reel, a chain upon the reel having a portion extending through an opening in the casing, a bearing plate resting against the 50 inner face of the reel and having a central opening and a peripheral notch, the rim of the reel having an opening registering with said notch, a spring abutting against said bearing plate, and a chain having one end 55 held in coincident openings of the said plate and rim.

4. In a device of the type set forth, the combination with a casing comprising a front plate and back plate, of a tubular bearing integral with the back plate, a reel within the casing comprising a rim, a body and a hub, said hub being located within the bearing, a spring connecting said bearing and body and surrounding the bearing, a bearing plate between said body and spring, and bearing against the inner face of the web of the reel, and a chain upon said rim, said bearing plate having a peripheral notch for co-operation with said chain. 70

5. In a device of the type set forth, the combination with a casing comprising a front plate and a back plate, of a tubular bearing rigid with the back plate, a reel within the casing comprising a rim, a body, 75 and a hub, said hub being located within said bearing, a spring connecting said bearing and body and surrounding the bearing, the web portion of said reel having a flange 80 of the same depth as the hub and provided with a lip, a spring having one end engaged with said lip, a bearing plate against which said spring abuts, said bearing plate surrounding the hub and bearing upon the inner face of the web of the reel. 85

In testimony whereof I have affixed my signature in presence of two witnesses.

CHARLES GOODWIN.
